UNITED STATES PATENT OFFICE

ALBERT E. PAGE, OF BROOKLYN, NEW YORK, ASSIGNOR TO SCOTT & WILLIAMS, INCORPORATED, OF NEW YORK, N. Y., A CORPORATION OF MASSACHUSETTS

TRANSFER RING FOR CIRCULAR KNITTING MACHINES

Original application filed May 8, 1929, Serial No. 361,418. Divided and this application filed March 5, 1930. Serial No. 433,378.

This application is a division of my copending application Serial No. 361,418 filed May 8, 1929 in which mechanism for controlling the movements of a transfer ring from inoperative to operative position is claimed.

This invention relates to mechanism for transferring a circular knitted web to the needles of a knitting machine, and more particularly to the type of transfer mechanism in which the loops of the fabric are transferred from the quills of a transfer ring on to the needles of a knitting machine, as for example, in putting the ribbed top of a half hose on to a plain knitting machine preparatory to the knitting of the leg and foot of the half hose.

It is an object of this invention to provide a transfer ring which is revoluble when it is desired to impale the stitches of a rib top upon the ring, but which may be fixed in a given position so that when the ring is inverted over the needle cylinder the quills of the transfer ring will register with the needles of the needle cylinder.

Another object is to provide a transfer ring which is composed of as few parts as possible and which is more economically practicable than prior transfer rings.

Other objects and advantages of my invention will appear as the invention is described in connection with the accompanying drawings.

In the drawings Fig. 1 is a perspective view of the new transfer mechanism partially inverted over the needle cylinder of the well known Scott and Williams type of seamless hosiery machine.

Fig. 2 is an elevation of the transfer ring in inverted position.

Fig. 3 is a vertical section through the transfer ring taken on the line 3-3 of Fig. 4.

Fig. 4 is a plan view of the top of the transfer ring when inverted showing the means of centering same.

Fig. 5 is a horizontal sectional view through the transfer ring taken on line 5-5 of Fig. 3.

Fig. 6 is an elevation of the transfer ring in retracted position partly in section taken on the line 6-6 of Fig. 7.

Fig. 7 is a horizontal section through the transfer ring taken on line 7-7 of Fig. 6.

While Fig. 8 is a vertical elevation of the transfer ring partly in section taken on the line 8-8 of Fig. 5.

The invention is shown embodied in the usual Scott & Williams type of seamless hosiery knitting machine having a revoluble needle cylinder 260 carried in a bed plate B with an outside sinker cam cap 300 and arm 550 of the latch ring for carrying the yarn fingers (not shown).

The transfer mechanism comprises a transfer ring carried by an arm 16 pivoted to swing about a pintle 15 supported on bracket 14 which in turn is supported upon the bed plate B of the machine. As shown in the drawings the carrier arm 16 is of such a shape that when retracted the transfer ring rests with its axis vertical with the quills q pointed upwardly (see Fig. 6) and with the transfer ring held revolvably in a manner which will be described in the subsequent paragraph. The carrier arm 16 can, if desired, be made of two parts, the lower part 167 and an upper 70 part 168, with set screws (not visible) joining the two parts adapted to provide vertical adjustment of the transfer ring relatively to the needle cylinder. The upper part 168 has four legs thereon to which the transfer 75 ring is attached in the following manner.

There is a circular mounting plate or pilot 169 secured by screws 184 to the various legs of the upper transfer ring arm 168, the exact 80 central position of this pilot being adjustable 85 by means of four chucking screws 181 passing radially through the central collar 169a of the pilot. This construction is shown in Figs. 3 and 4. Formed integrally with the pilot is a pilot sleeve 170 in the form of a 90 complete cylinder and extending perpendicularly from the pilot toward the quills. The pilot sleeve provides a firm well centered mounting for the transfer ring proper and the other parts about to be described. Fit-

ting loosely around the outside of this pilot sleeve 170 is a stripper ring 175 carrying the individual strippers 176 located between the individual quills q and adapted to strip the 95 terminal stitches and push them onto the 100

needles of the knitting machine. The transfer ring proper in the construction shown in the drawings is composed of a transfer ring base 171 slidably mounted outside the stripper 5 per ring 175, an inside transfer ring 174 on top of the base 171 and an outside transfer ring 173 threaded onto the upper end of the base and holding the inside transfer ring and quills assembled in position. The upper ends 10 of the strippers overlie the top of the inside transfer ring 174 in order that they may be intercalated between the quills q . To limit the sliding movement of the base 171 along the pilot sleeve 170 away from the pilot 169, 15 an external annular shoulder 171a is formed on and at the end of the base 171 adjacent the pilot. Cooperating with this shoulder are two adjustable U-bent transfer ring stops 172 each having its center portion parallel 20 to the transfer ring axis and having inwardly directed radial end portions one of which overlies the outer face of the pilot while the other is adapted to engage the annular shoulder 171a. The stops are secured to the periphery of the pilot by radial screws 172b 25 passing through slots in the central portions of the stops.

When the transfer ring is inverted over the needle cylinder and the base 171 is pushed 30 down toward the needles, the stops 172 catching under the shoulder 171a support the transfer ring proper from the pilot 169 and accurately define the degree of interengagement of the needles with the quills. In order 35 to vary this interengagement, adjusting screws 172a, which run parallel to the axis of the transfer ring, are threaded through those radially directed ends of the stops which overlie the outer face of the pilot 169. 40 Thus the ends of the adjusting screws will bear against the outer face of the pilot. By rotating the screws the position of the stops relative to the pilot may be varied and the range of movement of the base upon the pilot 45 sleeve may be regulated.

The stops may be locked in the position in which they are adjusted by means of the radially extending screws 172b.

In order that the stripper ring and strippers may have their movement relatively to the transfer ring limited to the proper extent, a small slot (see Fig. 3) is cut through the transfer ring base parallel to the axis thereof, and a radially directed screw 177 55 taking into the stripper ring is located in that slot. The ends of the slot serve to determine the limits of movement of the strippers relatively to the transfer ring.

For the purpose of actuating the transfer ring and the strippers an axle handle shaft 60 24 is provided which passes through the sleeve 169a of the pilot. An operating handle 25 is provided on the end of this handle shaft and a light compression spring 26 is 65 preferably located between this handle 25

and the sleeve 169a. On the inner end of this operating handle 24 two stripper operating fingers 178 are adjustably fastened by means of two screws 179 parallel to the axis of the ring and passing through slots 179a in the fingers, these fingers being laid side by side 70 on the end of the handle 24 and projecting in opposite directions transversely of the axis of the handle through openings 180 in the pilot sleeve 170. The ends of these operating fingers project into a circumferential groove in the inner surface of the stripper ring and the strippers therefore move in unison with the handle 24. The openings 180 in the vertical pilot sleeve are long 75 enough to permit advancement of the strippers to the necessary limit as defined by the stop screw 177 even when the transfer ring is farthest away from the pilot 169 with the quills q in engagement with the needles n 80 of the needle cylinder.

The transfer ring base 171 when resting on the top surface of the pilot 169 (see Figs. 3, 6, 8) is prevented from rotating relatively to the pilot by means of keys and complementary key-ways. In the drawings there are two keys 182 on the pilot projecting upwardly into keyways 183 on the lower edge of the transfer ring base 171. These keys fit into the keyways 183 without any lost motion and in this way the transfer ring is kept accurately in register with the needles. If it is desired to rotate the ring while the same is in retracted position in order to assist the operation of topping, i. e. putting the stitches of the ribbed top on the quills of the transfer ring, the transfer ring can be lifted away from the pilot as far as permitted by the ring stops 172. In this position the transfer ring base is above the tops of the keyways 183 and it is therefore possible to rotate the transfer ring. When two keyways are employed as shown in the drawings, it is preferable to make the keys dissimilar or to locate them in positions which are not diametrically opposed, 90 in order that the transfer ring may not drop down into register with the keys when half a revolution has been completed. In the drawings these keys and their complementary keyways are dissimilar and are located in positions which are not diametrically opposed, 95 It will be obvious that the complementary keyways will not both be in register with the keys at the same time when the transfer ring has been turned about one-half of a revolution, but of course when the ring has been turned 360° the keys and keyways will match 100 up simultaneously and the transfer ring will drop down onto the pilot in proper registry again. By having two keys and keyways 110 115 the transfer ring does not jam and is supported better than if only one were used.

In operation, when the transfer ring is inverted over the needle cylinder the transfer ring plunger spring 26 prevents the strip- 120 125 130

pers 176 from being inadvertently moved relatively to the quills *q* but the weight of the transfer ring base causes the ring to drop down to the position wherein it is supported by the stops 172 as shown in Fig. 2, keeping the strippers 176 in contact with the outer surface of the inside transfer ring 174. The quills are now in engagement with the needles *n* and the operator by pressing downwardly on handle 25 can advance the strippers and transfer the terminal loops of the ribbed top to needles of the knitting machine. Upon relieving the pressure from the handle 25 the spring 26 will cause the strippers to be retracted.

Certain subject matter shown and/or described, but not claimed herein, is claimed in the copending applications of Louis N. D. Williams, Serial No. 355,765 filed April 17, 20 1929 and Serial No. 381,791, filed July 29, 1929.

Thus it will be seen that I have provided a revoluble transfer ring composed of comparatively few parts and which is simple and positive in operation.

What I claim is:

1. A circular knitting machine having a revoluble needle cylinder, stitch transfer mechanism mounted on said machine and adapted to be swung into and out of operative relation with said needle cylinder, said transfer mechanism comprising a non-revoluble pilot, a plurality of keys on said pilot, a revoluble transfer ring on said pilot having keyways complemental to said keys, in combination with means permitting movement of said transfer ring away from said pilot sufficiently to free the keyways from said keys and permit rotation of the transfer ring.

2. A circular knitting machine having a revoluble needle cylinder, stitch transfer mechanism mounted on said machine and adapted to be swung into and out of operative relation with said needle cylinder, said transfer mechanism comprising a non-revoluble pilot, a revoluble transfer ring permanently attached to said pilot but having limited movement on said pilot, in combination with a sleeve on said pilot constituting a complete ring adjacent the outer end of said transfer ring.

3. A circular knitting machine having a revoluble needle cylinder, stitch transfer mechanism mounted on said machine and adapted to be swung into and out of operative relation with said needle cylinder, said transfer mechanism comprising a non-revoluble pilot, having a sleeve formed integrally therewith, in combination with a stripper ring revolubly mounted around said sleeve, a transfer ring base outside said stripper ring and having a limited movement on said pilot sleeve, and inside and outside transfer rings on said transfer ring base.

4. Transfer mechanism for a circular knit-

ting machine comprising a carrier arm, a pilot on said arm, a sleeve integral with said pilot, said sleeve forming a complete ring at its outer edge, there being openings in the walls of said sleeve below the outer edge, a stripper ring outside said sleeve and a transfer ring outside said stripper ring, in combination with a plunger passing axially through said pilot and operating means fastened to said plunger passing through the openings in the sleeve and engaging in a circumferential groove in said stripper ring, said stripper ring and said transfer ring being revoluble on said pilot.

5. Transfer mechanism for a circular knitting machine comprising a carrier arm, a pilot mounted in a nonrevoluble manner on said arm, chucking screws to center said pilot on said arm and a transfer ring permanently attached to said pilot but having limited movement on said pilot in combination with a plurality of complemental keys and keyways on said pilot and transfer ring, said complemental keys and keyways being dissimilar in plan, the limited movement of said transfer ring away from said pilot being sufficient to disengage the keys and keyways for rotation of the ring.

6. Stitch transfer mechanism for a circular knitting machine comprising a pilot, a transfer ring permanently attached to said pilot, stops permitting said transfer ring limited movement away from said pilot, a sleeve integral with said pilot and forming a complete ring at its upper edge, a stripper ring revolubly carried around said sleeve and means limiting the movement of said stripper ring, in combination with an axial plunger passing through said pilot and means on said plunger passing through openings in said sleeve and engaging in a continuous circumferential groove in said stripper ring to permit rotation of said stripper ring relative to said means.

In testimony whereof I have signed my name to this specification.
